US0D1012744S

(12) **United States Design Patent** (10) **Patent No.:** **US D1,012,744 S**
(45) **Date of Patent:** **** Jan. 30, 2024**

(54) **WEARABLE SENSOR WITH ILLUMINATED DISPLAY**

(71) Applicant: **BiolinQ Incorporated**, San Diego, CA (US)

(72) Inventor: **David Michael Morelock**, Escondido, CA (US)

(73) Assignee: **BiolinQ Incorporated**, San Diego, CA (US)

(**) Term: **15 Years**

(21) Appl. No.: **29/838,870**

(22) Filed: **May 16, 2022**

(51) **LOC (14) Cl.** **10-04**

(52) **U.S. Cl.**

USPC **D10/81**; D24/186; D24/216

(58) **Field of Classification Search**

(57) **CLAIM**

The ornamental design for a wearable sensor with illuminated display, as shown and described.

DESCRIPTION

FIG. 1 is a front view showing a first image in a sequence of a wearable sensor with illuminated display;

FIG. 2 is a front view showing a second image thereof;

FIG. 3 is a front view showing a third image thereof;

FIG. 4 is a front view showing a fourth image thereof;

FIG. 5 is a front view showing a fifth image thereof;

FIG. 6 is a front view showing a sixth image thereof;

FIG. 7 is a front view showing a seventh image thereof;

FIG. 8 is a front view showing an eighth image thereof;

FIG. 9 is a front view showing a ninth image thereof;

The appearance of the wearable sensor with illuminated display sequentially transitions between the images shown in FIGS. 1-9.

FIG. 10 is a front perspective view of the wearable sensor with illuminated display;

FIG. 11 is a top plan view thereof;

FIG. 12 is a bottom plan view thereof;

FIG. 13 is a left side view thereof;

FIG. 14 is a right side view thereof; and,

FIG. 15 is a rear view thereof.

FIGS. 10-15 are illustrative of the appearance of the wearable sensor shown in FIGS. 1-9 in a non-illuminated state. The process or period in which one image transitions to another forms no part of the claimed design. The stippling represents illumination, and the density of the stippling varies with the brightness of the illumination such that dense stippling represents brighter illumination than less dense stippling. The broken lines are for the purpose of illustrating portions of the wearable sensor and form no part of the claimed design.

1 Claim, 12 Drawing Sheets
